US0D1048745S

(12) **United States Design Patent** (10) Patent No.: **US D1,048,745 S**
(45) Date of Patent: ** Oct. 29, 2024

(54) **CHAIR**

(71) Applicant: **MUUTO A/S**, København K (DK)

(72) Inventors: **Torbjørn Anderssen**, Oslo (NO);
Espen Voll, Oslo (NO)

(73) Assignee: **MUUTO A/S** (DK)

(**) Term: **15 Years**

(21) Appl. No.: **35/517,403**

(22) Filed: **May 16, 2023**

(80) **Hague Agreement Data**

Int. Filing Date: **May 16, 2023**

Int. Reg. No.: **DM/229078**

Int. Reg. Date: **May 16, 2023**

Int. Reg. Pub. Date: **Jun. 2, 2023**

(30) **Foreign Application Priority Data**

Mar. 31, 2023 (EM) 015016579-0001

(51) **LOC (14) Cl.** **06-01**
